CLAIM

The ornamental design for a tape handle and dispenser combination, substantially as shown and described.

DESCRIPTION

FIG. 1 is a perspective view of a tape handle and dispenser combination having the new design. The optional strap holder attached to the bottom of the dispenser is shown in dashed lines; said strap holder is not a part of the claimed design.

FIG. 2 is a view from the top of the tape handle and dispenser combination shown in FIG. 1;

FIG. 3 is a front plan view of the tape handle and dispenser combination shown in FIG. 1, the view being identical as viewed from the back;

FIG. 4 is a left side plan view of the tape handle and dispenser combination shown in FIG. 1, the view being identical as viewed from the right side;

FIG. 5 is a view from below of the tape handle and dispenser combination shown in FIG. 1; and,

FIG. 6 is a perspective view of the tape handle and dispenser combination as shown in FIG. 1, with a sample of tape mounted for purposes of display. The tape itself is shown in dashed lines, and is not a part of the claimed design.
